UNITED STATES PATENT OFFICE.

VERGIL MULHOLLAND, OF WEST HARTFORD, CONNECTICUT, ASSIGNOR TO HARTFORD-EMPIRE COMPANY, OF HARTFORD, CONNECTICUT, A CORPORATION OF DELAWARE.

APPARATUS FOR ANNEALING GLASSWARE.

Application filed August 27, 1925. Serial No. 52,751.

The invention relates to apparatus for annealing glassware, and it has particular relation to lehrs of the tunnel type, through which articles of glassware are transported by an endless conveyor, and in which they are subjected to varying temperature environments, in order to relieve stresses and strains that may exist in the ware or that may develop therein after the ware is removed from the molds of the shaping machine.

One of the objects of the present invention is to improve upon the quality of annealing by providing a lehr of the character described having a plurality of heating flues associated with the walls of the tunnel, certain of which flues communicate with a fire box located adjacent to the entrance end of the tunnel, while certain others communicate with a fire box located at a point remote from the entrance end of the tunnel. The heated gases generated by the fire boxes are caused to flow through their respective flues in opposite directions, and by regulating either the intensity of the combustion in the fire boxes or the drafts in their associated flues, or both, the temperature in the tunnel may be caused to either rise or fall from the entrance end of the tunnel toward the exit end, and also by suitably regulating the combustion and draft, the drop in temperature of the heated gases from one fire box may be off-set or compensated for by a proportionally higher temperature produced by the gases from the other fire box, with the result that a substantially uniform temperature, both in vertical and longitudinal directions, may be obtained in that zone of the tunnel situated between the fire boxes.

In the accompanying drawings:

Figure 1 is a diagrammatic vertical longitudinal sectional view of the forward half of a lehr embodying the invention;

Fig. 2 is a similar view of the rear half of the lehr shown in Fig. 1; and

Fig. 3 is a vertical transverse sectional view taken on line 3—3 of Fig. 1.

Referring to the drawings, a lehr tunnel 1 is constructed of a plurality of substantially similar interchangeable sections 2 arranged in end-to-end relation, and is supported at intervals upon pedestals 3. Heating flues 4 and 5 extend longitudinally be-

neath the forward and rear portions of the tunnel, and each communicates through a damper-controlled passageway 6 with a common fire box 7 which is located beneath the lehr at a point remote from the entrance end of the tunnel. Dampers 8 and 9 are provided in the flues 4 and 5, respectively, at each side of the point where the passageway 6 communicates with these flues and may be selectively adjusted to independently regulate the drafts in these flues.

Heating flues 10 also extend longitudinally above the forward portion of the tunnel 1 and communicate at their forward ends with the forward ends of the heating flues 4 through damper-controlled passageways 11. The flues 10 also communicate through a damper-controlled passageway 13 with a fire box 12 located above the lehr adjacent to the entrance end of the tunnel. Cooling flues 14 extend longitudinally above the intermediate and rear portions of the tunnel 1 and communicate with the outer atmosphere adjacent to the exit or delivery end of the tunnel as indicated at 15 (Fig. 2). A plurality of damper-controlled openings or stacks 16, 17 and 18 are provided in the heating flues 5 and 10 and in the cooling flues 14, respectively, and establish communication between these flues and the outer atmosphere at intervals.

The heated gases from the fire boxes 7 and 12, and the cooling air from the outer atmosphere, are drawn through their respective heating and cooling flues 4, 5, 10 and 14 by a motor driven suction fan 19, which is mounted upon the tunnel adjacent to the exit end thereof (Fig. 2). This fan communicates with a wind box 20 which in turn communicates with the flues 5, through vertical branch pipes 21 disposed one on each side of the tunnel, and a damper-controlled passage 22 disposed beneath the tunnel.

The wind box 20 also communicates with a wind pipe 23, which extends longitudinally above the tunnel, and which communicates with the heating flues 10 through a damper-controlled stack 24 and with the cooling flues 14 through the stacks 18.

The location and arrangement of the flues 4, 5, 10 and 14 relative to the fan 19 and the location of the points where these

flues communicate with the fan and with the atmosphere is such that the action of this fan draws a portion of the heated gases from the fire box 7 through the flues 4 to-
5 ward the entrance end of the lehr, thence upwardly through the passageways 11 and rearwardly through the flues 10, the stack 24 and wind pipe 23. Another portion of the heated gases generated by the fire box
10 7 is drawn through the flues 5 toward the delivery end of the lehr, thence through the passageway 22, and upwardly through the pipe 21.

The heated gases from the fire box 12, 15 together with those drawn from the fire box 7, through the passageways 11, are also drawn rearwardly, that is, toward the discharge end of the lehr, through the heating flues 10 and the wind pipe 23. Cooling air 20 from the outer atmosphere is drawn through the flues 14 in a forward direction and flows into the wind pipe 23 through the stacks 18. Cooling air from the outer atmosphere is also drawn through the rear 25 portion of the flues 5 in a forward direction, from an inlet 25 (Fig. 2) and augments the effect of the cooling air in the flues 14 adjacent to the discharge end of the tunnel where it is desired to accelerate the cooling 30 of the annealed ware.

The top, bottom and side walls of the tunnel, throughout the greater portion of its length, are covered by suitable heat-insulating material 26 in order to minimize the dis-
35 sipation of heat therefrom. This covering preferably decreases in thickness toward the rear end of the tunnel, and terminates a short distance from the discharge end of the tunnel, so that the cooling of this portion of the tunnel may be assisted by the radia-
40 tion of heat from the walls thereof.

Glassware is transported through the tunnel by an endless conveyor 27, the ware-bearing strand of which traverses the tunnel and 45 is supported therein throughout its length and breadth by the flat bottom thereof, and the idle strand of which returns to the entrance end of the tunnel beneath the lehr, and is supported at intervals therebeneath
50 by rollers 28. This conveyor may be of any preferred construction and may be driven by any suitable mechanism, not shown.

By suitably adjusting the dampers 8 and 55 9 in the heating flues 4 and 5 and the dampers in the passageways 6, 11 and 13, the drafts in the heating flues may be independently controlled at will and by suitably adjusting the dampers in the stacks 16, 17 and 18 the amount of diluting and cooling air admitted into the flues 5 and 10 and the amount of cooling air withdrawn from the cooling flues 14 may be also controlled at will. The location of such admissions and withdrawals may also be selectively controlled, as desired.
60 65

The illustrated embodiment of the invention may be modified in construction, arrangement and mode of operation without departing from the scope of the invention, as defined in the appended claims.

I claim:

1. Apparatus for annealing glassware comprising a tunnel, a plurality of flues associated with said tunnel, a fire box communicating with one of said flues at a point adjacent to the entrance end of said tunnel, a fire box communicating with another of said flues at a point remote from the entrance end of said tunnel, and means for causing heated gases to flow through the portions of said flues located between said fire boxes in opposite directions with respect to each other. 70 75 80 85

2. Apparatus for annealing glassware comprising a tunnel, a flue extending longitudinally along a wall of said tunnel, a flue extending longitudinally along another wall of said tunnel, a fire box communicating with one of said flues at a point adjacent to the entrance end of said tunnel, a fire box communicating with the other of said flues at a point remote from the entrance end of said tunnel, and means for causing heated gases to flow through the portions of said flues located between said fire boxes in opposite directions with respect to each other. 90 95 100

3. Apparatus for annealing glassware comprising a tunnel, a flue extending longitudinally above said tunnel, a flue extending longitudinally below said tunnel, a fire box communicating with one of said flues at a point adjacent to the entrance end of said tunnel, a fire box communicating with the other of said flues at a point remote from the entrance end of said tunnel, and means for causing heated gases to flow through the portions of said flues located between said fire boxes and in opposite directions with respect to each other. 105 110 115

4. Apparatus for annealing glassware comprising a tunnel, a flue extending longitudinally above said tunnel, a flue extending longitudinally below said tunnel, a fire box communicating with the upper flue at a point adjacent to the entrance end of said tunnel, a fire box communicating with the lower flue at a point remote from the entrance end of said tunnel, and means for causing heated gases to flow through the portions of said flues located between said fire boxes in opposite directions with respect to each other. 120 125 130

5. Apparatus for annealing glassware, comprising a tunnel, a plurality of flues associated with said tunnel and extending longitudinally thereof, a fire box communicating with each of said flues, and means for causing heated gases from one of said fire boxes to flow in one direction in the flues communicating therewith and the gases from 130

the other of said fire boxes to divide and flow in opposite directions in the flues communicating with such fire box.

6. A lehr comprising a tunnel, a flue associated therewith, and means for causing heated gases to flow through a portion of said flue to heat a portion of said tunnel and for causing a cooling medium to flow through another portion of said flue to cool another portion of said tunnel.

7. A lehr comprising a tunnel, a flue associated therewith, and means for causing heated gases to flow through a portion of said flue to heat a portion of said tunnel and for causing a cooling medium to flow through another portion of said flue in a direction opposite to that of the flow of said gases to cool another portion of said tunnel.

8. A lehr comprising a tunnel, a flue associated therewith, and means for causing heated gases to flow through a portion of said flue to heat a portion of said tunnel and for causing cooling air to flow through another portion of said flue to cool another portion of said tunnel.

9. A lehr comprising a tunnel, a flue associated therewith, and means for causing heated gases to flow through a portion of said flue to heat a portion of said tunnel and for causing cold air from the outer at-

mosphere to flow through another portion of said flue in a direction opposite to that of the flow of said gases to cool another portion of said tunnel.

10. A lehr comprising a tunnel, a flue disposed beneath said tunnel, means for causing heated gases to flow through a portion of said flue to heat a portion of said tunnel and air from the outer atmosphere to flow through another portion of said flue in a direction opposite to that of the flow of said gases to cool another portion of said tunnel, and means for controlling the volume of air admitted to said flue.

11. A lehr for annealing glassware, comprising a tunnel, and means for causing a heating medium and a cooling medium to flow adjacent to different portions of a wall of said tunnel to respectively heat and cool different zones in said tunnel.

12. A lehr for annealing glassware, comprising a tunnel, and means for causing a heating medium and a cooling medium to flow adjacent to different portions of a wall of said tunnel and in opposite directions with respect to each other to respectively heat and cool different zones in said tunnel.

Signed at Hartford, Connecticut, this 25th day of August, 1925.

VERGIL MULHOLLAND.
